Inventor,

Ota Tafts

United States Patent Office.

OTIS TUFTS, OF BOSTON, MASSACHUSETTS.

Design No. 4,020, dated May 10, 1870.

DESIGN FOR OVERHEAD WORK FOR PASSENGER-ELEVATOR CARS.

The Schedule referred to in these Letters Patent and making part of the same

To all whom it may concern:

Be it known that I, OTIS TUFTS, of Boston, in the county of Suffolk and State of Massachusetts, have originated and designed a new Design for the Overhead construction and finish of the Passenger-Cars for Elevators, of which the following is a full and exact description, reference being had to the accompanying drawings and to the letters of reference marked thereon.

The drawing represents a view, from beneath, of the design.

The overhead work shown in the accompanying drawing is made of wood, cast-iron, or other suitable material, and is a plate of a rectangular form, consisting of one or more pieces, with a center, *m m*, and a margin or rim, *k*, united together by the radial bars *a b c d e f g h*, with openings 1 2 3 4 5 6 7 8 between them.

The center, bars, and rim are all flush upon the under side, and I have shown them as made plain; but I propose to ornament them in various ways, the center *m*, for instance, carrying a center-piece of carved or other work, and the radial bars and rim may be embellished by panel-work, frescoing, &c

The open spaces may be occupied by open, scroll or net-work.

What I claim as my invention, and desire to secure by Letters Patent, is—

The design for overhead work in passenger-elevator cars, herein set forth.

OTIS TUFTS.
